UNITED STATES PATENT OFFICE

163,643

BASE FOR POWER MOWERS

Gerald J. Shaw, Kansas City, Kans., assignor to
Propulsion Engine Corporation, Kansas City,
Kans., a corporation of Missouri

Application December 21, 1950, Serial No. 13,526

Term of patent 3½ years

(Cl. D40—1)

To all whom it may concern:

Be it known that I, Gerald J. Shaw, a citizen of the United States, residing at Kansas City, in the county of Wyandotte and State of Kansas, have invented a new, original, and ornamental Design for a Base for Power Mowers, of which the following is a specification, reference being had to the accompanying drawing, forming a part thereof, wherein:

Fig. 1 is a top perspective view of a base for power mowers, showing my new design.

Fig. 2 is a top plan view thereof; and

Fig. 3 is a side elevational view.

I claim:

The ornamental design for a base for power mowers, as shown.

GERALD J. SHAW.
